UNITED STATES PATENT OFFICE.

JOHN M. LEBENS, OF JORDAN, MINNESOTA.

BOX AND BUCKLE DEVICE FOR HARNESS.

SPECIFICATION forming part of Letters Patent No. 716,253, dated December 16, 1902.

Application filed May 3, 1902. Serial No. 105,744. (No model.)

To all whom it may concern:

Be it known that I, JOHN M. LEBENS, a citizen of the United States, residing at Jordan, in the county of Scott and State of Minnesota, have invented certain new and useful Improvements in Box and Buckle Devices; and I do hereby declare the following to be a full, clear, and exact description of the invention, such as will enable others skilled in the art to which it appertains to make and use the same.

My invention has for its object to provide an improved box and buckle device for harnesses; and to this end it consists of the novel devices and combinations of devices herein-after described, and defined in the claims.

The invention is illustrated in the accompanying drawings, wherein like characters indicate like parts throughout the several views.

20 Fig. 1 is a plan view with some parts broken away, showing a box designed in accordance with my invention and also a buckle and strap which coöperates therewith. Fig. 2 is a side or edge elevation of the said parts. 25 Fig. 3 is a longitudinal section on the line $x^3 x^3$ of Fig. 1, some parts being left in full. Fig. 4 is a transverse section on the line $x^4 x^4$ of Fig. 3. Fig. 5 is a plan view of a strap from which the body of the box is formed, 30 and Fig. 6 is a plan view of the so-called "spacing loop" or "piece."

As is well known, boxes of this character are provided at various places in harnesses for receiving the ends of straps—such as breeching-straps, collar-tugs, bridle-checks, and the like. Usually these boxes have been formed by bending a wide strip of leather around a heavy back piece and sewing the edges thereto.

In accordance with my invention I use only 40 a flat piece or pieces of leather in connection with a marginal spacing strip or loop and run a single seam through the edges of the same.

The character a indicates the strip which forms the body of the box, and the character b indicates the rectangular marginal spacing-strip, both of which parts are preferably of leather. The strap a is preferably slightly reduced in width at a' and a'' , and in line with the reduced section a'' it is provided with a 45 slit a^3 , through which the tongue c of an ordinary buckle c' is adapted to be passed. After the tongue of the buckle is inserted

through the slit a^3 the short projecting end of the strap is turned over and back onto the body of the strap, as shown in Figs. 2 and 3. 55 A metal loop f is slipped onto the strap a down to the reduced portion a' , and then the long projecting end of the said strap is turned over onto the body, but between the same and the body is first placed the marginal spacing 60 strip or loop b . The overlapped parts are then sewed together by a heavy seam g .

The character k indicates the strap which coöperates with the buckle c and which may be assumed to be either a breech-strap, collar-tug, or bridle-check. The end of this strap k is adapted to be inserted into the opening or interior a^4 of the box-like housing afforded by the strap a and spacing-strip b and it is of course evident that the said spacing-strip b should be as thick or preferably a little thicker than the said strap k , and that the difference between its longitudinally-extended side should be a little greater than the width of the said strap k , so as to make 70 the insertion and removal of said strap an easy matter. It will be noted that the spacing loop or strip b is beveled, as shown at b' , and that in line therewith the end of the strap a is beveled, as shown at a^5 , to afford an entrance-passage for the strap k into the cavity or interior a^4 . Of course this entrance-passage might be afforded by entirely cutting away the end of the spacing-loop b ; but the construction described is stronger than the 75 modification suggested, for the reason that the seam g may be run through the body and backturned end of the strap a and through both ends of the said spacing-loop, so that the one reinforces and strengthens the other. 80

It will of course be understood that the device above described is capable of some modification within the scope of my invention as herein set forth and claimed.

What I claim, and desire to secure by Letters Patent of the United States, is as follows:

1. The combination with the buckle c and strap k , of parallel box-forming sections, and a marginal spacing-strip interposed between the edges of said parallel strap-sections, the 100 edges of said box-forming strap-sections and the said spacing-strip being sewed together, and one of said strap-sections, at the open end of the box, being projected farther than

the other and secured to said buckle, substantially as described.

2. The combination with the buckle *c* and strap *k*, of the box-forming strap *a* connected to said buckle and folded upon itself, and the marginal spacing - strip interposed between the overlapped sections of said strap *a*, the edges of which strap *a* and of said spacing-strip are sewed together, substantially as described.

3. The combination with the buckle *c*, loop *f* and strap *k*, of the box-forming strap *a* reduced at *a'* and *a²*, provided with the slit *a³* and beveled at *a⁵*, which strap is folded upon

itself to form the body of the strap-receiving box, and which buckle and loop are secured to said strap as described, and the spacing-loop *b* beveled at *b'* and interposed between the overlapped sections of said strap *a* and which strap *a* and spacing-loop *b* are sewed together by a marginal seam *g*, substantially as described.

In testimony whereof I affix my signature in presence of two witnesses.

JOHN M. LEBENS.
